SIGNALING SYSTEM

Neal D. Newby, Leonia, N. J., assignor to Bell Telephone Laboratories, Incorporated, New York, N. Y., a corporation of New York

Application August 19, 1943, Serial No. 499,187

11 Claims. (Cl. 179—27)

This invention relates to signaling systems and particularly to telephone systems arranged for voice frequency signaling.

Objects of the invention are the improvement of signaling systems in which signals consist of current impulses of each of a plurality of frequencies in succession and the provision of a simple, efficient and dependable signal transmitting arrangement for such systems.

The invention is a signaling system in which signals consist of a plurality of alternating current impulses in succession, each impulse of a different frequency, and in which an enablement or gate-opener signal consisting of an impulse of current of one frequency followed by an impulse of current of another frequency is transmitted to enable response to selective or supervisory signals consisting of current of a third frequency. A feature of the invention is the provision of two delay networks in the signal transmitter of such a system to control the transmission of the two impulses of current which constitute an enablement of signal, one of the networks being effective to measure the interval for the first impulse of the enablement signal and the other network being effective to measure the interval for the second impulse of the enablement signal.

A clear and complete description of the invention will be facilitated by considering a system arranged in accordance with the invention and its various features, one such system being shown in the drawings which forms a part of this specification. The invention is, however, not limited in its application to the system shown in the drawings but is generally applicable to signaling systems in which signals are transmitted by current of each of a plurality of frequencies in succession.

Referring to the drawings:

Figs. 1 and 2 represent in a toll office of a telephone system, an operator's position OP, an outgoing trunk circuit OT¹, a two-way trunk circuit TWT¹, a toll route selector TS¹, a toll line circuit TLC¹, a signal transmitter circuit ST¹ and a signal receiver circuit SR¹ all associated with an intertoll trunk line TL¹. Fig. 1 further shows an incoming trunk circuit IT¹; and

Fig. 3 shows a second toll line circuit TLC², a signal transmitter ST² and a signal receiver SR² associated with an intertoll trunk line TL².

The system represented in the drawings includes a plurality of toll offices, each of which comprises operators' positions with cords for answering calls incoming from local manual or dial

offices, from toll subscribers' lines, from community dial offices, and from other toll offices; and for extending incoming calls to switching trunks leading to called manual and dial local offices, to trunks to community dial offices, to intertoll trunks, and to toll subscribers' lines. Answering jacks are directly connected to recording trunks, toll subscribers' lines, trunks from community dial offices and intertoll trunks. Outgoing jacks are connected to switching trunks, toll lines, trunks to community dial offices and intertoll trunks. Toll route selectors and auxiliary toll route selectors are provided in one or more of the offices for use on calls incoming over intertoll trunks to establish connections with called toll, local, or community dial offices. The operators' positions are provided with dials for use in controlling the operation of incoming and auxiliary toll route selectors in other toll offices and for controlling the operation of selector and connector switches in local or community dial offices. Reference may be had to the patent to R. E. King et al., No. 2,209,777, granted July 30, 1940, for a disclosure of such a system in which composite signaling circuits are provided for the transmission of signals over the intertoll trunks between the various toll offices.

The operators' position equipment including the telephone, dial and cords, the outgoing trunk circuit OT¹, two-way circuit TWT¹, toll route selector TS¹, and incoming trunk circuit IT¹ may be similar to like circuits disclosed in the aforementioned patents to R. E. King et al. The signal receiver SR¹ may be similar to that disclosed in the copending application of N. D. Newby et al., Ser. No. 499,186, filed Aug. 19, 1943.

The toll line circuit TLC¹ comprises a repeating coil 212, a directionally selective coil 211, and a cut-off relay 210 for disconnecting the talking conductors of the outgoing trunk circuit OT¹ from, and connecting the associated signal transmitter ST¹ to, the intertoll trunk line TL¹. The directionally selective coils 211 transmit signaling current incoming over toll line TL¹ through conductors 213 and 214 to the signal receiver SR¹ without substantial attenuation and transmit voice currents and signaling current from signal transmitter ST¹ to the repeating coil 212 without substantial attenuation. But the coils 211 prevent any substantial portion of the signal energy transmitted by the transmitter ST¹ from passing into the signal receiver SR¹, thereby to prevent false operations and to prevent interference with the response of the signal receiver SR¹ to incoming signals.

The signal transmitter ST1 comprises signal relays 230 and 231 operatively controlled by relay 110 of the outgoing trunk circuit OT1, relays 232 and 234 controlled by relay 231, relays 240, 241, 250 and 251 controlled by relay 230, relay 260 jointly controlled by relays 234, 241 and 251, two delay networks N1 and N2, and a transformer 236 through which impulses of current of each of three signaling frequencies are transmitted under the direct control of relays 232, 240, 250 and 260. The upper winding of relay 232 is normally connected in series with condenser 233; and, when relay 231 operates, condenser 233 charges through the lower winding of relay 232 to effect the operation of relay 232 for a desired interval of time. The network N1 delays the response of relays 240 and 241 to each operation and each release of relay 230 for a predetermined desired interval of time, and the network N2 further delays the response of relays 250 and 251 for a desired predetermined interval of time, thereby to measure the intervals during which impulses of current of each of the various frequencies are transmitted. The value of such delay networks is in the independence of the delay interval from variations of battery potentials and variations in pulsing speed. These are low pass filters and the pulsing frequency is less than the cut-off frequencies of the filters. With this type of delay circuit the delay may be greater than the time between pulses if required. Relays 230, 240 and 250 are polarized relays each having a biasing winding and one or two operating windings. The contacts are shown in normal position, and each of these relays is referred to herein as being released when the contacts are in this position. Relays 232 and 260 control the circuit for operating the cut-off relay 210 of the toll line circuit. Each of the sources of signaling current G1, G2 and G3 may be a vacuum tube oscillator or other known source of current of desired frequency.

The signal transmitter ST1 is arranged to transmit seizure, selective, ringing and disconnect signals on calls outgoing over trunk line TL1, and to transmit off-hook, all-trunks busy, called-line-busy, on-hook and disconnect-acknowledgement signals on incoming calls. A seizure signal consists of an impulse of current of frequency f_1 followed by an impulse of current of frequency f_2 . A train of dial impulse signals is preceded by an enablement signal consisting of an impulse of current of frequency f_2 followed by an impulse of current of frequency f_1 . Each dial impulse of the train is transmitted by current of frequency f_3 ; and current of frequency f_1 is transmitted at the end of each dial impulse until the next dial impulse begins or for a predetermined interval following the last dial impulse of a train. A ringing signal consists of the enablement signal followed successively by an impulse of current of frequency f_3 and an impulse of current of frequency f_1 , the same as for a single dial impulse. A disconnect signal consists of the enablement signal followed by a relatively long impulse of current of frequency f_3 and differs from a single dial impulse signal in that the current of frequency f_3 is not followed by current of frequency f_1 . An off-hook signal, transmitted when an incoming call is answered, is similar to a seizure signal on an outgoing call. An on-hook signal is similar to a disconnect signal. An all-trunks-busy or called-line-busy condition effects the alternate transmission of off-hook and on-hook signals.

Assume now that relay 110 of trunk circuit OT1 has operated responsive to insertion of the calling

plug CPI of a cord CD1 into jack J1 in the manner described in the aforementioned King et al. patent. The operation of relay 110 closes a circuit through conductor 115 for operating relays 230 and 231 of signal transmitter ST1. The operation of relay 231 closes a circuit for charging condenser 233 and operatively energizing the lower winding of relay 232. The operation of relay 232 causes the operation of relay 234 and the release of cut-off relay 210 of line circuit TLC1, thereby to connect the transformer 236 to the toll line TL1. The operation of relay 232 closes a circuit from signaling current source G1, through the left contacts of relays 240 and 250, left winding of transformer 236, to ground at a front-contact of relay 232, thereby transmitting current of frequency f_1 through transformer 236 and coils 211 and 212 to toll line TL1. The operation of relay 230 opens the normally closed circuit through the lower windings of relays 240 and 250 and closes the circuit through the middle winding of relay 240, winding of relay 241, middle winding of relay 250 and winding of relay 251. The delay network N1 delays the response of relays 240 and 241 to the operation of relay 230 for about .025 second after the operation of relay 232, the operation of relay 240 being effective to connect the signaling current source G2 to the lower winding of transformer 236 in place of source G1, thus ending the transmission of current of frequency f_1 and initiating the transmission of current of frequency f_2 . The upper winding of relay 250 is normally energized under the control of relay 260; and as long as this winding is energized, the contacts of relay 250 are held in normal position. The networks N1 and N2 delay the response of relay 251 to the operation of relay 230 by the seizure signal and delays the response of both of relays 250 and 251 to operations of relay 230 occurring after the upper winding of relay 250 is deenergized as hereinafter described. The operation of relay 251 connects ground to one side of the lower winding of relay 260, but this winding is not energized until relay 241 releases as hereinafter described. Relay 232 releases when the current charging condenser 233 falls below the operating level, this being about .100 second after relay 232 operates. The release of relay 232 opens the circuit through the left winding of transformer 236 to terminate the transmission of current of frequency f_2 , the impulse of current of frequency f_2 being about .050 second in length. Thus the seizure of trunk circuit OT1 effects the transmission of a seizure signal consisting of current of frequency f_1 for about .025 second followed by current of frequency f_2 for about .050 second.

When relay 110 is alternately released and re-operated responsive to trains of dial impulses created by the dialing of the digits of the toll route code and local office code, and also the called subscriber's number on calls to subscribers in dial offices, relays 230 and 231 are alternately released and reoperated. The release of relay 230 in response to the first dial impulse of each train opens the circuit for energizing the middle windings of relays 240 and 250 and the windings of relays 241 and 251 and closes the circuit for energizing the lower windings of relays 240 and 250, the release of relays 240 and 241 being delayed by network N1 and the release of relay 251 being delayed by both of networks N1 and N2. The release of relay 231 closes a circuit for discharging condenser 233 through the lower winding of relay 232, thereby to operate relay 232 for about .100 second. The operation of relay 232

causes the operation of relay 234, causes the release of cut-off relay 210, and closes a circuit from ground at the inner front contact of relay 232, through the left winding of transformer 236, back contact of relay 250, front contact of relay 240, and the source of signaling current G2. The transmission of an impulse of current of frequency f_2 is thereby initiated. About .025 second after relay 232 reoperates, relays 240 and 241 release. The release of relay 240 connects the source G1 to the lower winding of transformer 236 in place of source G2 thereby to end the transmission of current of frequency f_2 and initiate the transmission of current of frequency f_1 through transformer 236 and line TL1. Since relay 251 is operated at the time that relay 241 releases, the lower winding of relay 260 is thereby operatively energized. Relay 260 closes a locking circuit through its upper winding under the control of relay 234, opens the circuit through the upper winding of relay 250 to render this relay responsive to each release and reoperation of relay 230, and closes a circuit for energizing the upper winding of relay 240 thereby to prevent the reoperation of relay 240 while relay 230 is responding to the succeeding dial impulses of a train. The cut-off relay 210 cannot reoperate until both of relays 232 and 260 releases; and the signal transmitting circuit through the left winding of transformer 236 remains closed as long as either of relays 232 and 260 remains operated. About .025 second after relays 240 and 241 release, relay 250 operates due to the deenergization of its middle winding and energization of its lower winding. At the same time relay 251 releases opening the operating circuit through the lower winding of relay 260, relay 260 being held operated under the control of relay 234. The operation of relay 250 connects the signaling current source G3 to the lower winding of transformer 236 in place of source G1 thereby terminating the transmission of current of frequency f_1 and initiating the transmission of current of frequency f_3 through transformer 236 and toll line TL1. Since the charging and discharging of condenser 233 is effective to maintain the operative energization of the one or the other of the windings of relay 232 while relay 231 is responding to a train of dial impulses, relay 232 remains operated during the transmission of a train of dial impulses and does not release until an interval of .100 second has elapsed following the reoperation of relay 231 at the end of the last dial impulse of the train. The operating winding of relay 260 is reenergized for about .025 second in response to each release of relay 230. When relay 250 releases, about .050 second after the reoperation of relay 232 at the end of each dial impulse, it ends the transmission of current of frequency f_3 and initiates the transmission of current of frequency f_1 . When relay 250 reoperates, about .050 second after the reoperation of relay 230 at the beginning of each succeeding dial impulse of the train, it ends the transmission of current of frequency f_1 and initiates the transmission of current of frequency f_3 . When relay 260 releases, due to the continued operation of relays 236 and 231 at the end of the last dial impulse of a train, the current of frequency f_1 is ended by the opening of the circuit through the lower winding of transformer 236. Relays 234 and 260 are slow in releasing so that the interval elapsing between the reoperation of relay 231 and the release of relay 260, at the end of the last impulse of a train, is greater than the longest

allowable dial impulse plus the delay introduced by both of the delay circuits N1 and N2, thereby insuring that an impulse of frequency f_1 follows the current of frequency f_3 representing the last dial impulse of the train. The release of relay 260 closes the circuit for operating the cut-off relay 210, opens the circuit energizing the upper winding of relay 240 and closes the circuit through the upper winding of relay 250. At this time, relays 230 and 231 are operated, relays 232, 234 and 260 are released, relays 240, 241 and 251 are operated, relay 250 is released and relay 210 is operated. Thus the two networks N1 and N2 are effective to delay the response of relays 240 and 250 to each release and reoperation of relay 230 for an interval sufficient to permit the sending of an enablement or gate-opener signal consisting of current of frequency f_2 for about .025 second followed by current of frequency f_1 for about .025 second preceding the current of frequency f_3 which represents the first dial impulse of a train.

To transmit a ringing or rering signal, relay 110 of outgoing trunk circuit is momentarily released due to the operation of a ringing key by the calling operator in the manner set forth in the aforementioned King et al. patent, thereby effecting the momentary release and reoperation of relays 230 and 231. The signal transmitter ST1 is thus rendered effective to transmit a ringing signal which consists of the enablement signal followed by current of frequency f_3 for the duration of the release of relay 230 followed by current of frequency f_1 until relay 260 releases. It is apparent that the transmission of a ringing signal is effected in the same manner as that of a dial impulse train consisting of a single dial impulse.

When the calling operator removes the plug CPI from jack J1, relay 110 is released in the manner set forth in the aforementioned King et al. patent, thereby causing the release of relays 230 and 231. The release of relays 230 and 231 causes the transmission of the enablement signal consisting of current of frequency f_2 for about .025 second followed by current of frequency f_1 for about .025 second and causes the transmission of current of frequency f_3 immediately following the enablement signal. The current of frequency f_3 is not followed by current of frequency f_1 , as in the case of the transmission of a single dial impulse, because relays 230 and 231 do not reoperate; and when relay 260 releases, it ends the transmission of current of frequency f_3 . While the signal transmitter ST1 is not so arranged, it may readily be modified to effect the repeated transmission of the disconnect signal until a disconnect-acknowledgment signal is received by the signal receiver SR1, in which case the signal transmitter is also arranged to transmit a disconnect-acknowledgment signal on incoming calls responsive to a disconnect signal being received by the signal receiver SR1.

On an incoming call, the relay 220 of signal receiver SR1 is operated by a seizure signal transmitted over line TL1 from a signal transmitter at its distant end. Reference may be had to the aforementioned copending application of N. D. Newby et al. for a description of the manner in which relay 220 is operated responsive to an incoming seizure signal. The operation of relay 220 connects ground to conductor 114 thereby causing the operation of relays 120, 121 and 122 of two-way trunk circuit TWT1 in the manner described in the aforementioned King et al. patent. Relay 122 connects ground to conductor 133 to hold the

connection thereafter established. Relay 220 repeats dial impulses over conductor 114 to operate selector TS1 in the manner set forth in the aforementioned King et al. patent. Assuming the call is completed through selector TS1 to an incoming trunk circuit OT1, relay 161 is operated, in series with relay 121 of two-way trunk circuit TWT1, to light the answering lamp AL. When an operator answers the call by inserting the answering plug of a cord in jack AJ, relay 164 is operated in the manner described in the aforementioned King et al. patent to connect ground to conductor 154, thence through brush 144 of selector TS1, and conductor 134, to operate relay 124 of two-way trunk circuit TWT1. The operation of relay 124 closes a circuit for operating relays 230 and 231 of signal transmitter ST1 thereby to effect the transmission of an off-hook supervisory signal over line TL1 in the same manner that a seizure signal is transmitted on an outgoing call as hereinbefore described. If the answering operator disconnects, relay 164 releases and an on-hook supervisory signal is transmitted by signal transmitter ST1 in the same manner that a disconnect signal is transmitted on an outgoing call as hereinbefore described. If the selector TS1 encounters an all-trunks-busy condition, or if the called subscriber's line is busy on a call to a subscriber in a dial office, relay 124 is alternately operated and released in the manner set forth in the aforementioned King et al. patent, thereby to cause the transmitter ST1 to send a succession of off-hook and on-hook signals over line TL1.

Assume now that the toll line circuit TLC2, signal transmitter ST2 and signal receiver SR2, shown in Fig. 3, are associated with the trunk circuit OT1 of Fig. 1 in place of the corresponding circuits shown in Fig. 2. The signal transmitter ST2 uses rectifier arrangements in place of relay contacts for initiating and ending the transmission of impulses of current of each of the three signal frequencies. The sources G1, G2 and G3 of frequencies f_1 , f_2 , and f_3 are connected by transformers 340, 350 and 360, pairs of rectifiers 343 and 344, 355 and 356, and 365 and 366, and transformers 349, 359 and 369 to contacts of the cut-off relay 310 of line circuit TLC2. The transmission of current from each of these sources to toll line TL2 depends upon whether the associated pair of rectifiers has a high or a low impedance, the impedance of each pair of rectifiers being high when there is substantially no direct current therethrough and low when the direct current therethrough is sufficiently large to effect such a result. The impedance of the three pairs of rectifiers is controlled by relays 335, 336 and 337 as hereinafter described. The lowest windings of relays 335 and 337 are not required unless it is necessary to bias the dial impulse signals to correct for distortion.

When relay 110 operates responsive to seizure of outgoing trunk circuit OT1, it closes a circuit for operating relays 330 and 331 of signal transmitter ST2. The operation of relay 330 opens the normally closed circuit through the middle windings of relays 335 and 337 and closes a circuit for energizing the upper windings of these relays, the response of relay 335 to each operation and release of relay 330 being delayed by network N1 and the response of relay 337 being delayed by both of networks N1 and N2. The operation of relay 331 connects condenser 333 to the lower winding of relay 332 whereby relay 332 is operated by the current charging condenser 333 for about .100 second. The operation of relay 332

causes the operation of slow-to-release relay 334 and the release of cut-off relay 310 of line circuit TLC2. With relay 334 operated and relay 310 released, the transformers 349, 359 and 369 are connected through coils 311 and 312 to toll line TL2. At this time a direct current circuit exists from ground through the back contact of relay 335, conductor 338, resistors 341 and 342, rectifiers 343 and 344, resistors 347 and 348, and through resistor 345 to negative battery. The current in this circuit is of sufficient amplitude and has the proper polarity to reduce the impedance of rectifiers 343 and 344 whereby current of frequency f_1 is transmitted from source G1, through transformer 340, rectifiers 343 and 344 and transformer 349 to toll line TL2. At this time there is a direct current circuit through resistor 353 and rectifier 354 and the current therein reduces the impedance of rectifier 354 so that it constitutes a substantial short circuit across the rectifiers 355 and 356; and the high impedance of rectifiers 355 and 356 prevents the transmission of current of frequency f_2 from source G2 through transformer 359 to line TL2. At this same time, negative battery is connected through resistors 363, 362 and 361 to one side of these rectifiers and a like potential is applied through resistor 345, rectifier 346 and resistors 367 and 368 to the other side of these rectifiers; and since there is no direct current through rectifier 365 and 366, the high impedance of rectifiers 365 and 366 prevents the transmission of current of frequency f_3 through transformer 369 to line TL2. When relay 335 operates, about .025 second after 332 operates, it opens the direct current circuit through rectifiers 343 and 344 and the impedance of these rectifiers increases to end the transmission of current of frequency f_1 to line TL1. The operation of relay 335 also opens the direct current circuit through rectifier 354, whereby the impedance of rectifiers 355 and 356 is reduced by direct current in a circuit from battery through resistors 353, 352 and 351, rectifiers 355 and 356, and resistors 357 and 358 to ground. The reduction of the impedance of rectifiers 355 and 356 effects the transmission of current of frequency f_2 from source G2 through transformers 350 and 359 to toll line TL2. When relay 332 releases, about .100 second after its operation, it closes the circuit for reoperating the cut-off relay 310, thereby ending the transmission of current of frequency f_2 to line TL2. The release of relay 332 also causes the release of relay 334. The operation of relay 331 about .025 second after the operation of relay 335 is ineffective to cause the operation of relay 336 while relay 335 remains operated. Thus a seizure signal, consisting of an impulse of current of frequency f_1 for .025 second followed by an impulse of current of frequency f_2 for about .050 second, is transmitted over line TL2.

When a train of dial impulses is repeated by relay 110 of outgoing trunk circuit OT1, relays 330 and 331 are alternately released and reoperated. Each release and reoperation of relay 330 causes a delayed release and reoperation of relays 335 and 337. The first release of relay 331 causes the operation of relay 332 and each succeeding reoperation and release of relay 331 causes the alternate energization of the two windings of relay 332 so that relay 332 remains operated during the response of relay 331 to dial impulses. The operation of relay 332 causes the operation of relay 334 and the release of cut-off relay 310; and relay 334 connects the right wind-

ings of transformers 349, 359 and 369 to the line TL2, whereby current of frequency f_2 is transmitted from source G2 through transformer 359, rectifiers 355 and 356 and transformer 359 to toll line TL2. When relay 335 releases in response to the first dial impulse about .025 second after relay 332 operates, ground is reconnected to conductor 338 thereby ending the transmission of current of frequency f_2 and initiating the transmission of current of frequency f_1 through rectifiers 343 and 344 and transformer 349 to line TL2. Since relay 337 remains operated for about .025 second after relay 335 releases, the release of relay 335 opens the short circuit across the lower winding of relay 336 thereby effecting the operation of relay 336. Relay 336 locks through its upper winding under control of relay 334, connects ground to conductor 338 and connects conductor 339 to the back contact of relay 337. When relay 337 releases, .025 second after relay 335 releases in response to the first dial impulse, ground is connected to conductor 339; whereby direct current through rectifier 346 reduces the impedance of rectifier 346 so that rectifiers 343 and 344 are short-circuited and their impedance becomes high to end the transmission of current of frequency f_1 . The connection of ground to conductor 339 also results in a direct current through rectifiers 365 and 366; whereby the impedance of these rectifiers is reduced to initiate the transmission of current of frequency f_3 from source G3 through transformer 366, rectifiers 365 and 366 and transformer 369 to toll line TL2. The current of frequency f_3 continues until relay 337 reoperates responsive to the reoperation of relay 330 at the end of the first dial impulse. Since relay 336 maintains the connection of ground to conductor 338 until all the dial impulses in the train have been received by relays 330 and 331 and transmitted over toll line TL2, the operation and release of relay 335 in response to succeeding dial impulses of the train are without effect. When relay 337 reoperates responsive to the release of relay 330 at the end of the first dial impulse, conductor 339 is disconnected from ground so that transmission of current of frequency f_3 is ended and transmission of current of frequency f_1 is initiated. The release and reoperation of relay 337 responsive to each succeeding dial impulse of the train effects the connection of ground to, and disconnection of ground from, conductor 339 thereby effecting the transmission of current of frequency f_3 for the duration of each dial impulse and the transmission of current of frequency f_1 during the interval between successive dial impulses of the train. After the last impulse of the train, relay 337 remains operated so that the current of frequency f_1 continues until relay 334 releases about .150 second after the reoperation of relay 337. The release of relay 334 causes the release of relay 336 and the reoperation of relay 310.

A ringing signal is transmitted in the same manner that the transmission of one dial impulse is effected responsive to the dialing of the digit 1. A disconnect signal is transmitted in the same manner that the transmission of one dial impulse representing the digit 1 is effected, except that the current of frequency f_3 is not followed by current of frequency f_1 ; since relay 337 remains released, the current of frequency f_3 continues until relay 334 releases.

While the signal transmitter shown in Fig. 3 is not so arranged, it may readily be modified to repeat the transmission of the disconnect sig-

nals on outgoing calls until a disconnect-acknowledgment signal is received by the associated signal receiver and to transmit a disconnect-acknowledgment signal on incoming calls in response to a disconnect signal incoming to the associated signal receiver. These and other modifications are within the scope of the invention.

What is claimed is:

1. In a voice frequency signaling system, a signal transmitter for converting direct current signals into alternating current signals, said transmitter comprising first and second relays responsive to the closing and opening of a direct current signaling circuit, three sources of alternating current, each source of a different frequency, means including third and fourth relays controlled by said second relay, a battery for use in operating said third and fourth relays, a delay network connected in series with said battery and the contacts of said second relay and the windings of said third and fourth relays to delay for a predetermined interval of time the response of said third and fourth relays to operations of said second relay, another delay network connected in series with said battery and the windings of said third and fourth relays to further delay for a predetermined interval of time the response of said fourth relay to operations of said second relay, means including said first relay for transmitting an impulse of current of a first one of the three frequencies, means comprising said third relay for terminating the impulse of current of said first frequency and for transmitting an impulse of current of a second one of the three frequencies, and means comprising said fourth relay for terminating the impulse of current of said second frequency and for transmitting an impulse of current of the third frequency.

2. In a voice frequency signaling system, a signal transmitter comprising relay means responsive to trains of impulses corresponding to numerical digits, first and second relays controlled by said relay means, a first delay network delaying the response of said first relay to the operation of said relay means in response to the first impulse of a numerical train, a second delay network, said first and second delay networks delaying the response of said second relay to the operation of said relay means in response to the first impulse of a numerical train, means controlled by the operation of said relay means in response to the first impulse of a numerical train for initiating the transmission of an impulse of current of a first one of three signaling frequencies, means effective upon operation of said first relay to terminate the impulse of current of said first frequency and to initiate an impulse of current of a second one of said three frequencies, means effective upon operation of said second relay to terminate the impulse of current of said second frequency and to initiate an impulse of current of the third of said frequencies, means comprising said second relay for terminating the transmission of the impulse of said third frequency after an interval of time equal to the length of the first numerical impulse of the train received by said relay means and for thereafter alternately effecting the transmission of impulses of current of said second and third frequencies for intervals of time respectively equal to the duration of the intervals between numerical impulses in a train and the duration of the numerical impulses and for transmitting an impulse of current of said second frequency of predetermined duration following the impulse of current of said third frequency cor-

responding to the last numerical impulse of a train received by said relay means.

3. In combination, signal receiving means comprising a first relay and a second relay controlled by direct current signals, three sources of alternating current, each source of a different frequency, means comprising a third relay and a fourth relay for transmitting alternating current signals, a battery, a first plurality of retard coils and condensers, one winding of each of said retard coils being connected in series with said battery and a front contact of said first relay and one winding of said third relay, another winding of each of said retard coils being connected in series with said battery and a back contact of said first relay and another winding of said third relay, and each of said condensers being connected across the windings of said retard coils to form with said retard coils a delay network for delaying for a predetermined interval of time the response of said third and fourth relays to each operation and release of said first relay, a second plurality of retard coils and condensers, one winding of each of said second plurality of retard coils being connected in series between said one winding of said third relay and one winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, means rendered effective by the release of said second relay to initiate the transmission of current from a first one of said sources, means rendered effective by the response of said third relay to the release of said first relay to end the transmission of current from said first source and to initiate the transmission of current from a second one of said sources, and means rendered effective by the response of said fourth relay to the release of said first relay to end the transmission of current from said second source and to transmit current from the third one of said sources.

4. In combination, signal receiving means comprising a first relay and a second relay controlled by direct current signals, three sources of alternating current, each source of a different frequency, means comprising a third relay and a fourth relay for transmitting alternating current signals, a first plurality of retard coils and condensers, one winding of each of said retard coils being connected in series between a front contact of said first relay and one winding of said third relay, another winding of each of said retard coils being connected in series between a back contact of said first relay and another winding of said third relay, and each of said condensers being connected across the windings of said retard coils to form with said retard coils a delay network for delaying for a predetermined interval of time the response of said third and fourth relays to each operation and release of said first relay, a second plurality of retard coils and condensers, one winding of each of said second plurality of retard coils being connected in series between said one winding of said third relay and one winding of said fourth relay, another winding of each of said second plurality of retard coils being connected in series between said one winding of said third relay and one winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, means responsive to the operation of said second relay for initiating the transmission of current from a first one of said sources, means rendered effective by the response of said third relay to the operation of said first relay to end the transmission of current from said first source and to initiate the transmission of current from a second one of said sources, means effective a predetermined interval of time after the operation of said second relay for ending the transmission of current from said second source, means responsive to the release of said second relay for initiating the transmission of current from said second source, means rendered effective by the response of said third relay to the release of said

said other winding of said first relay and another winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, means rendered effective by the release of said second relay to initiate the transmission of current from a first one of said sources, means rendered effective by the response of said third relay to the release of said first relay to end the transmission of current from said first source and to initiate the transmission of current from a second one of said sources, means rendered effective by the response of said fourth relay to the release of said first relay to end the transmission of current from said second source and to initiate the transmission of current from the third one of said sources, and means rendered effective by the continued release of said second relay to end the transmission of current from said third source.

5. In combination, signal receiving means comprising a first relay and a second relay controlled by direct current signals, three sources of alternating current, each source of a different frequency, means comprising a third relay and a fourth relay for transmitting alternating current signals, a first plurality of retard coils and condensers, one winding of each of said retard coils being connected in series between a front contact of said first relay and one winding of said third relay, another winding of each of said retard coils being connected in series between a back contact of said first relay and another winding of said third relay, and each of said condensers being connected across the windings of said retard coils to form with retard coils a delay network for delaying for a predetermined interval of time the response of said third relay to each operation and release of said first relay, a second plurality of retard coils and condensers, one winding of each of said second plurality of retard coils being connected in series between said one winding of said third relay and one winding of said fourth relay, another winding of each of said second plurality of retard coils being connected in series between said other winding of said first relay and another winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, means responsive to the operation of said second relay for initiating the transmission of current from a first one of said sources, means rendered effective by the response of said third relay to the operation of said first relay to end the transmission of current from said first source and to initiate the transmission of current from a second one of said sources, means effective a predetermined interval of time after the operation of said second relay for ending the transmission of current from said second source, means responsive to the release of said second relay for initiating the transmission of current from said second source, means rendered effective by the response of said third relay to the release of said

first relay to end the transmission of current from said second source and initiate the transmission of current from said first source, means rendered effective by the response of said fourth relay to the release of said first relay to end the transmission of current from said second source and initiate the transmission of current from the third of said sources, and means responsive to the continued release of said second relay for ending the transmission of current from said third source.

6. In combination, signal receiving means comprising a first relay and a second relay controlled by direct current signals, three sources of alternating current, each source of a different frequency, means comprising a third relay and a fourth relay for transmitting alternating current signals, a first plurality of retard coils and condensers, one winding of each of said retard coils being connected in series between a front contact of said first relay and one winding of said third relay, another winding of each of said retard coils being connected in series between a back contact of said first relay and another winding of said third relay, and each of said condensers being connected across the windings of said retard coils to form with said retard coils a delay network for delaying for a predetermined interval of time the response of said third relay to each operation and release of said first relay, a second plurality of retard coils and condensers, one winding of each of said second plurality of retard coils being connected in series between said one winding of said third relay and one winding of said fourth relay, another winding of each of said second plurality of retard coils being connected in series between said other winding of said first relay and another winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, means responsive to the operation of said second relay for initiating the transmission of current from a first one of said sources, means rendered effective by the response of said third relay to the operation of said first relay to end the transmission of current from said first source and initiate the transmission of current from a second one of said sources, means effective a predetermined interval of time after the operation of said second relay for ending the transmission of current from said second source, means responsive to the release of said second relay for initiating the transmission of current from said second source, means rendered effective by the response of said third relay to the release of said first relay to end the transmission of current from said second source and initiate the transmission of current from the third of said sources, means responsive to the reoperation of said fourth relay within a predetermined interval of time after its release for ending the transmission of current from said third source and for initiating the transmission of current from said first source, and means responsive to the continued operation of said second relay for ending the transmission of current from said first source.

7. In combination, signal receiving means comprising a first relay and a second relay controlled by direct current signals, three sources of alternating current, each source of a different frequency, means comprising a third relay and a fourth relay controlled by said first and second relays for transmitting alternating current signals, a first plurality of retard coils and condensers, one winding of each of said retard coils being connected in series between a front contact of said first relay and one winding of said third relay, another winding of each of said retard coils being connected in series between a back contact of said first relay and another winding of said third relay, and each of said condensers being connected across the windings of said retard coils to form with said retard coils a delay network for delaying for a predetermined interval of time the response of said third relay to each operation and release of said first relay, a second plurality of retard coils and condensers, one winding of each of said second plurality of retard coils being connected in series between said one winding of said third relay and one winding of said fourth relay, another winding of each of said second plurality of retard coils being connected in series between said other winding of said first relay and another winding of said fourth relay, and each of said second plurality of condensers being connected across the winding of said second plurality of retard coils to form with said retard coils a second delay network for delaying the response of said fourth relay to each operation and release of said first relay for a predetermined interval of time after the response of said third relay, means responsive to the operation of said second relay for initiating the transmission of current from a first one of said sources, means rendered effective by the response of said third relay to the operation of said first relay to end the transmission of current from said first source and initiate the transmission of current from a second one of said sources, means effective a predetermined interval of time after the operation of said second relay for ending the transmission of current from said second source, means responsive to the release of said second relay for initiating the transmission of current from said second source, means rendered effective by the response of said third relay to the release of said first relay to end the transmission of current from said first source and initiate the transmission of current from the third of said sources, means responsive to the reoperation of said fourth relay within a predetermined interval of time after its release for ending the transmission of current from said third source and for initiating the transmission of current from said first source, means responsive to the continued operation of said second relay for ending the transmission of current from said first source, and means responsive to the continued release of said second relay for ending the transmission of current from said third source.

8. In a voice frequency signaling system, a signal transmitter for converting direct current signals into alternating current signals, said transmitter comprising first and second relays responsive to the closing and opening of a direct current signaling circuit, three sources of alternating current, each source of a different fre-

quency, means including third and fourth relays controlled by said second relay, a battery for use in operating said third and fourth relays, a delay network connected in series with said battery and the contacts of said second relay and the windings of said third and fourth relays to delay for a predetermined interval of time the response of said third and fourth relays to operations of said second relay, another delay network connected in series with said battery and the windings of said third and fourth relays to further delay for a predetermined interval of time the response of said fourth relay to operations of said second relay, said network being so arranged and connected that said delay intervals are independent of variations in the voltage of said battery.

9. In combination, signal receiving means comprising a first relay and a second relay controlled by direct current signals, three sources of alternating current, each source of a different frequency, means comprising a third relay and a fourth relay for transmitting alternating current signals, a battery, a first plurality of retard coils and condensers, one winding of each of said retard coils being connected in series with said battery and a front contact of said first relay and one winding of said third relay, another winding of each of said retard coils being connected in series with said battery and a back contact of said first relay and another winding of said third relay, and each of said condensers being connected across the windings of said retard coils to form with said retard coils a delay network for delaying for a predetermined interval of time the response of said third and fourth relays to each operation and release of said first relay, a second plurality of retard coils and condensers, one winding of each of said second plurality of retard coils being connected in series between said one winding of said third relay and one winding of said fourth relay, and each of said second plurality of condensers being connected across the windings of said second plurality of retard coils to form with said retard coils a second delay network for delaying the response of said fourth relay to each operation and release of said first relay for a predetermined interval of time after the response of said third relay, said network being so arranged and connected that said delay intervals are independent of variations in the voltage of said battery.

10. In combination, signal receiving means comprising a first relay and a second relay, both controlled by direct current signals, third and fourth relays controlled by said second relay, first and second delay networks, each consisting of a plurality of retard coils and condensers bridged across the windings of the retard coils, said first delay network connected between the contacts of said second relay and the windings of said third relay and said second delay network connected between said windings of said third relay and windings of said fourth relay, whereby the response of said third relay to the operation and release of said second relay is delayed for a predetermined interval of time and the response of said fourth relay to the operation and release of said second relay is delayed for a further predetermined interval of time, a fifth relay, means including a condenser and contacts of said first relay for operatively energizing said fifth relay

for a predetermined interval of time responsive to the operation and responsive to the release of said first relay, a line, means including a sixth relay operated responsive to the operation of said fifth relay for initiating the transmission of current of a first one of three signaling frequencies over said line, means responsive to the operation of said third relay for terminating the transmission of current of said first frequency and for initiating the transmission over said line of current of a second one of said signaling frequencies, means controlled by said fifth relay for ending the transmission of current of said second frequency a predetermined interval of time after the operation of said first relay and for initiating the transmission of current of said second frequency responsive to the release of said first relay, means including a seventh relay operated responsive to the release of said third relay while said fourth relay is operated, the release of said third relay a predetermined interval of time after the release of said second relay being effective to end the transmission of current of said second frequency and initiate the transmission of current of said first frequency, means including said sixth relay for holding said seventh relay independent of said third and fourth relays, and means responsive to each release of said fourth relay while said seventh relay is operated for ending the transmission of current of said first frequency and for initiating the transmission of current of said third frequency and responsive to each operation of said fourth relay while said seventh relay is operated for ending the transmission of said third frequency and initiating the transmission of said first frequency, the release of said fifth relay being effective to end the transmission of said first frequency.

11. In combination, signal receiving means comprising a first relay and a second relay, both controlled by direct current signals, third and fourth relays controlled by said second relay, first and second delay networks, each consisting of a plurality of retard coils and condensers bridged across the windings of the retard coils, said first delay network connected between the contacts of said second relay and the windings of said third relay and said second delay network connected between said windings of said third relay and windings of said fourth relay, whereby the response of said third relay to the operation and release of said second relay is delayed for a predetermined interval of time and the response of said fourth relay to the operation and release of said second relay is delayed for a further predetermined interval of time, a fifth relay, means including a condenser and contacts of said first relay for operatively energizing said fifth relay for a predetermined interval of time responsive to the operation and responsive to the release of said first relay, a line, a source of current of a first frequency, a source of current of a second frequency, a source of current of a third frequency, means including variable impedance rectifiers individual to each of said sources for connecting said sources to said line, means including a sixth relay operatively controlled by said fifth relay for completing the connection between said sources and said line, means for reducing the impedance of the rectifiers associated with said first source to effect the transmission of current of said first frequency over said line when said sixth relay is operated until said third relay operates, means for increasing the impedance of the rectifiers associated with said first source and de-

creasing the impedance of the rectifiers associated with said second source when said third relay operates to end the transmission of current of said first frequency and initiate the transmission of current of said second frequency over said line, a seventh relay, means rendered effective by the release of said fifth relay while said seventh relay is normal for ending the transmission of current of said second frequency without changing the impedance of the rectifiers associated with said second source and rendered effective by the reoperation of said fifth relay responsive to the release of said first relay for again initiating the transmission over said line of current of said second frequency, the release of said third relay being effective to increase the impedance of the rectifiers associated with said second source to end the transmission of current of said second frequency and to decrease the impedance of the rectifiers associated with said first source to initiate the transmission of current of said first frequency over said line, means for operating said seventh relay when said third relay releases while

5 said fourth relay is operated, means for locking said seventh relay under control of said sixth relay, and means effective while said seventh relay is operated to prevent the reducing of the impedance of the rectifiers associated with said second frequency, to increase the impedance of the rectifiers associated with said first source and reduce the impedance of the rectifiers associated with said third source each time said fourth relay 10 releases to end the transmission of current of the first frequency and initiate the transmission of current of the third frequency, and to increase the impedance of the rectifiers associated with said third source and decrease the impedance of the rectifiers associated with said first source each time said fourth relay operates to end the transmission of current of the third frequency and initiate the transmission of current of the first frequency, the release of said sixth relay being 15 effective to end the transmission of current of either said first or said third frequencies.
